US00D857655S

(12) **United States Design Patent** (10) **Patent No.:** **US D857,655 S**
(45) **Date of Patent:** **** Aug. 27, 2019**

(54) **HEADPHONES**

(71) Applicant: **Dolby Laboratories Licensing Corporation**, San Francisco, CA (US)

(72) Inventors: **Lucas E. Saule**, San Francisco, CA (US); **Vincent Voron**, Menlo Park, CA (US); **Peter Michaelian**, Tappan, NY (US); **Guangyu Jin**, San Francisco, CA (US); **Kevin J. Kilpatrick**, Mountain View, CA (US); **Branko Lukic**, Menlo Park, CA (US); **Steven Ryutaro Takayama**, Menlo Park, CA (US); **Grayson H. Byrd**, San Francisco, CA (US); **Adam Scott Koniak**, Redwood City, CA (US); **Ariel Laurent Fischer**, San Francisco, CA (US); **Robert Edward Borchers**, Pleasanton, CA (US)

(73) Assignee: **Dolby Laboratories Licensing Corporation**, San Francisco, CA (US)

(**) Term: **15 Years**

(21) Appl. No.: **29/638,590**

(22) Filed: **Feb. 28, 2018**

Related U.S. Application Data

(63) Continuation of application No. 29/556,705, filed on Mar. 2, 2016, now abandoned.

(51) **LOC (12) Cl.** **14-01**

(52) **U.S. Cl.**

USPC **D14/205**

(57) **CLAIM**

The ornamental design for headphones, as shown and described.

DESCRIPTION

FIG. 1 shows a perspective view of headphones showing our new design;

FIG. 2 shows another perspective view thereof;

FIG. 3 shows a front view thereof;

FIG. 4 shows a rear view thereof;

FIG. 5 shows a top thereof; and,

FIG. 6 shows a bottom view thereof.

The dashed broken lines illustrate structure or features which form no part of the claimed design.

(Continued)

The dot-dash broken lines illustrate boundaries of the claimed design; the boundaries themselves form no part of the claimed design.

1 Claim, 5 Drawing Sheets
